[57] CLAIM

The ornamental design for a stackable utility basket, as shown and described.

DESCRIPTION

FIG. 1 is a perspective view of a stackable utility basket embodying my new design;

FIG. 2 is a top plan view thereof; and

FIG. 3 is a cross-sectional view on line 3—3 of FIG. 2. The bottom of the basket is substantially a planar surface except for the rib shown in FIG. 3 which extends continuously around the bottom surface.

FIG. 2

FIG. 3
